DESIGN FOR A GARMENT HANGER

Edward B. Farmer, St. Johnsbury, Vt.

Application January 19, 1935, Serial No. 54,936

Term of patent 7 years

To all whom it may concern:

Be it known that I, Edward B. Farmer, a citizen of the United States, residing at St. Johnsbury, in the county of Caledonia and State of Vermont, have invented a new, original, and ornamental Design for a Garment Hanger, of which the following is a specification, reference being had to the accompanying drawing, forming part thereof.

I claim:

The ornamental design for a garment hanger, as shown and described.

EDWARD B. FARMER.
